AUTOMATIC FIREARM

Filed May 22, 1929

UNITED STATES PATENT OFFICE

FRITZ HERLACH AND THEODOR RAKÜLA, OF DÜSSELDORF, GERMANY, ASSIGNEES TO
RHEINISCHE METALLWAAREN- UND MASCHINENFABRIK, OF DÜSSELDORF-DERENDORF, GERMANY

AUTOMATIC FIREARM

Application filed May 22, 1929, Serial No. 365,108, and in Germany June 4, 1928.

Our invention relates to an automatic fire arm having a sliding barrel and a longitudinally movable locked breech which is opened during the recoil to eject the empty cartridge case and to supply a new cartridge. In fire arms of this class an advance in recoil has to be imparted to the breech piece relatively to the recoiling barrel, after the breech piece has been unlocked, in order to obtain in due time 10 a sufficient space for the introduction of a new cartridge. In long-recoil fire arms of high ballistic power and using cartridges of a comparatively great length the known recoil increasing lever inserted between the barrel and breech piece is unable to impart to the breech piece the required acceleration in rearward direction, owing to its acting on the breech piece only on a short section of the recoil. This known lever is further exposed to 15 rapid wear due to its blow-like unelastic action.

Now according to our invention the required recoil acceleration is imparted to the breech piece by an accelerating mechanism 20 that operates elastically. To this end a spring comes to act upon the breech piece after the barrel and the breech piece have been unlocked from one another during the common recoil, which spring has been tensioned 25 during the first section of the recoil and imparts to the breech piece a rearward acceleration relatively to the barrel which continues recoiling. By suitably determining the 30 spring as to power and relaxing stroke, our accelerating mechanism can be adapted without difficulty to the conditions of any fire arm so that the power required to accelerate during recoil the breech piece relatively to the 35 barrel can be obtained for every fire arm.

In order that our invention can be more readily understood, an embodiment of the same is illustrated by way of example in the accompanying drawings in which

Figure 1 is a longitudinal section through the parts entering in consideration of a fire arm, the parts being in run out position and the breech locked.

Figure 2 is a similar section showing the 50 parts when recoiling after the shot in the

instant the accelerating spring starts to be tensioned.

Figure 3 is a similar section showing the parts during the further recoil shortly before the completely tensioned accelerating 55 spring is released, and

Figure 4 shows the same parts when the breech piece is separated from the barrel by the released and relaxing spring.

Referring to these drawings, *a* denotes the 60 barrel which is mounted for longitudinal shifting motion in the casing *b* and the portion *a*₁ of which, that rearwardly extends beyond the cartridge chamber of the barrel forms the breech wherein the breech piece *c* is lodged. The latter may be designed as a rotary screw breech. In a bore *a*₃ of a casing *a*₂ laterally arranged on the barrel *a* is lodged the accelerating spring *d*. This spring abuts with its front end on the front wall *a*₄ of the 65 bore *a*₃ and with its rear end on a piston *e* shiftable in the bore *a*₃. The piston *e* has fixed on it a rod *e*₁ which extends through the partition *a*₄ and a chamber *a*₅ situated in front thereof. On its front end the rod *e*₁ 70 has a head *e*₂ which when the barrel is in run out position abuts on the front wall *b*₂ of a lateral casing portion *b*₁ that encases the accelerating mechanism. Between the head *e*₂ and the partition *a*₄ is inserted a buffer 75 *f* that e. g. consists of annular friction springs. In the piston *e* is pivoted a lever *g* which under the action of a spring *g*₁ projects into a recess *b*₃ of the case portion *b*₁. The rear wall of this recess is 80 formed by a slope face *b*₄. The piston *e* has further pivoted in it another two-armed lever *h*, *h*₂ the head *h*₁ of which can be swung by a spring *h*₃ into the path of a lug *c*₁ rigid 85 on the breech piece *c*. When the accelerating spring *d* is in relaxed state, this lug *c*₁ is swung back to inoperative position into the piston *e* by the other arm *h*₂ of lever *h* *h*₂ striking a stop face *a*₆ of the barrel casing *a*₂.

When a shot has gone off, the barrel *a* and the breech piece *c* bolted thereto execute from the run out position, Figure 1, the first section of the recoil in unison. This motion is taken part in by the rod *e*₁ until the lever *g* mounted in the piston *e* strikes the slope face *b*₄ of the 90 100

case b_s , Figure 2, so that in the further course of the recoil the piston e is stopped and the accelerating spring d is compressed. When this takes place first the stop a_6 is shifted 5 to the rear relatively to piston e and releases the lever arm h_2 whereupon the head h_1 of arm h rushes into the path of the lug c_1 of the breech piece c . Then the breech piece c is released in known manner from the barrel 10 a and its lug c_1 passes past the head h_1 of lever h which elastically gives way and again rushes into engaging position. Shortly thereafter a forward stop face a_7 of the casing a_2 lifts the locking lever g to such an extent that 15 it glides upward on the slope face b_4 , see Figure 3.

The accelerating spring d which is now fully compressed is then able to relax and pushes the piston e to the rear, Figure 4, 20 which latter imparts to the breech piece c an acceleration beyond the recoil motion relatively to the barrel a that likewise recoils farther a short distance, until spring d has relaxed completely. The breech piece c thus 25 moves off from barrel a and this motion on the one hand takes place with such a power that the extraction of the cartridge case still 30 in the cartridge chamber of barrel a is warranted, and, on the other hand, so far to the rear that the space required for the introduction of a new cartridge is abundantly at disposal between barrel a and breech piece c , the latter moving back still farther due to its 35 inertia after the accelerating spring d has completely relaxed. When spring d has relaxed, the head e of rod e_1 strikes the buffer spring f which elastically takes up the living force of the recoiling accelerating members.

When the running out motion begins under 40 the action of the running out device (not shown), the described accelerating mechanism d, e, e_1, e_2 is entrained, the head h_1 of lever h being rocked out of the path of the lug c_1 of breech piece c to initial position within 45 in piston e by the stop face a_6 rocking the arm h_2 . At the end of the running out motion the head e_2 of the rod e_1 strikes the wall b_2 of case b_1 and the buffer spring f elastically takes up the running out force. Lever g again 50 enters the recess b_s , as shown in Figure 1, and the breech piece again assumes closing position under the action of a closing spring (not shown).

What we claim and desire to secure by Letters Patent is:—

1. An automatic fire arm comprising a shiftable barrel; a locking breech, said barrel and breech unlocking from one another during the common recoil motion; and a spring which has been tensioned during the first section of the recoil adapted to act upon the breech to impart to it a lead that is an acceleration relatively to the barrel in the recoil direction.

2. An automatic fire arm comprising a cas-

ing; a shiftable barrel in said casing; a locking breech, said barrel and breech unlocking from one another during the common recoil motion; a stop in the barrel; an accelerating piston adapted to be shifted longitudinally relatively to the barrel; an accelerating spring inserted between the stop and the piston; and a locking member which is adapted to lock said piston during the first action of the recoil relatively to the casing to tension the spring, and after the locking member has been positively released during the recoil causes the power accumulated in the accelerating spring to act upon the breech piece 70

3. An automatic fire arm comprising a casing; a shiftable barrel in said casing; a locking breech, said barrel and breech unlocking from one another during the common recoil motion; a stop in the barrel; an accelerating piston adapted to be shifted longitudinally relatively to the barrel; an accelerating spring inserted between the stop and the piston which has been tensioned during the first section of the recoil adapted to act upon the breech to impart to it a lead that is an acceleration relatively to the barrel in the recoil direction; and a locking member which is adapted to lock said piston during the first action of the recoil relatively to the casing to tension the spring, and after the locking member has been positively released during the recoil causes the power accumulated in the accelerating spring to act upon the breech piece 75

4. An automatic fire arm according to claim 3 in which the release of the locking member takes place by the action of the barrel.

5. An automatic fire arm comprising a casing; a shiftable barrel in said casing; a locking breech, said barrel and breech unlocking from one another during the common recoil motion; a stop in the barrel; an accelerating piston adapted to be shifted longitudinally relatively to the barrel; an accelerating spring inserted between the stop and the piston which has been tensioned during the first section of the recoil adapted to act upon the breech to impart to it a lead that is an acceleration relatively to the barrel in the recoil direction; a locking member which is adapted to lock said piston during the first action of the recoil relatively to the casing to tension the spring, and after the locking member has been positively released during the recoil causes the power accumulated in the accelerating spring to act upon the breech piece 80

6. An automatic fire arm comprising a casing; a shiftable barrel in said casing; a lock-

ing breech, said barrel and breech unlocking from one another during the common recoil motion; a stop in the barrel; an accelerating piston adapted to be shifted longitudinally relatively to the barrel; an accelerating spring inserted between the stop and the piston which has been tensioned during the first section of the recoil adapted to act upon the breech to impart to it a lead that is an acceleration relatively to the barrel in the recoil direction; a locking member which is adapted to lock said piston during the first action of the recoil relatively to the casing to tension the spring, and after the locking member has been positively released during the recoil causes the power accumulated in the accelerating spring to act upon the breech piece; and a driver adapted to temporarily couple the piston with the breech piece and is positively retired when the accelerating spring is in relaxed state in the piston to inoperative position and goes over to the position to couple it with the breech piece only when the accelerating spring is tensioned and in which a buffer is provided which is adapted to damp the arrival of the accelerating members rushing back under the action of said spring to recoil end position.

7. An automatic fire arm comprising a casing; a shiftable barrel in said casing; a locking breech, said barrel and breech unlocking from one another during the common recoil motion; a stop in the barrel; an accelerating piston adapted to be shifted longitudinally relatively to the barrel; an accelerating spring inserted between the stop and the piston which has been tensioned during the first section of the recoil adapted to act upon the breech to impart to it a lead that is an acceleration relatively to the barrel in the recoil direction; a locking member which is adapted to lock said piston during the first action of the recoil relatively to the casing to tension the spring, and after the locking member has been positively released during the recoil causes the power accumulated in the accelerating spring to act upon the breech piece; and a driver adapted to temporarily couple the piston with the breech piece and is positively retired when the accelerating spring is in relaxed state in the piston to inoperative position and goes over to the position to couple it with the breech piece only when the accelerating spring is tensioned and in which a buffer is provided which is adapted to damp the arrival of the accelerating members rushing back under the action of said spring to recoil end position and is further adapted to damp the barrel when arriving in run out position.

In testimony whereof we have affixed our signatures.

FRITZ HERLACH.
THEODOR RAKULA.
